LINER HANGER AND SETTING TOOL
Amos D. Springer, Long Beach, Calif., assignor to Alad
Oil Tool, Inc., Long Beach, Calif., a corporation of
California
Filed Oct. 31, 1961, Ser. No. 149,056
16 Claims. (Cl. 166—120)

This invention relates to subsurface well completion equipment and more particularly to a packer-type liner hanger adapted to be run into and set in well casings and the like pipe strings in earth bore holes.

A principal object of the present invention is to furnish a casing liner hanger which can be run into a well casing on a suspending means, such as tubing or pipe, set at any chosen depth therein, a pack-off effected between the liner hanger and casing, and finally a detachment of the suspending means from the liner hanger for withdrawal from the well, all by right hand rotational and longitudinal manipulation of such suspending means.

Another object of the present invention is to furnish a liner hanger which can be set in any chosen location in a wall casing without the necessity of first touching bottom to actuate or control the setting mechanism.

Another object of the present invention is to furnish a liner hanger which can be run into well casing on a suspending means, such as tubing or pipe and by manipulating of the suspending means, set at any chosen depth therein, a pack-off effected between the liner hanger and the casing and then, if desired, released from such set and packed-off condition and moved to and reset at another location in the well.

Another object of this invention is to provide a liner hanger which is self-centering in the casing, thereby insuring proper positioning of the suspending liner or pipe in the well and the proper functioning of the suspending slips and the packing.

Another object of this invention is to furnish a liner hanger which has a substantially uniform bore extending therethrough from end to end and which is substantially unobstructed upon release and removal of the setting tool therefrom.

The objects of this invention are attained in general by a liner hanger and setting tool assembly having slips actuatable by the setting tool for supporting it in a well casing, pack-off means actuatable by the setting tool for sealing the annular space between the hanger and surrounding casing, and detachment means actuatable by the setting tool for releasing the setting tool from the liner hanger for withdrawal from the well after the setting operations are completed, all such operations being performed entirely by combined rotational and longitudinal manipulation of the liner hanger and setting tool upon a suspending, operating string. More specifically, the objects are attained by a liner hanger and setting tool assembly of the aforesaid construction which is provided with slips and means for first setting the slips into supporting engagement with the casing at any chosen location in the well by rotation of the setting tool relative to the hanger body, after which the setting tool can be lowered relative to the thus supported hanger body to a position where continued rotation of the setting tool relative to the hanger body actuates means therein to set the packing to seal off the annular space between hanger body and surrounding casing, and finally, in turn, the setting tool can be moved longitudinally to still another position relative to the hanger body where still further rotation of the setting tool relative to the hanger body actuates means to disconnect the setting tool from the hanger body, permitting the setting tool to be withdrawn from the well leaving the liner hanger set in the well casing.

2

A distinctive feature of this invention resides in its design which permits the setting tool to suspend the liner and liner hanger weight on the operating string in such manner as to leave the operating string freely rotatable to operate the slip mechanism and the pack-off mechanism or any other desired device before disengaging from the liner hanger.

An important advantage of the construction afforded by the liner hanger of the present invention also resides in the relatively thin-walled, large, unobstructed-bore, tubular structure which it provides.

These and other objects, advantages, and features of novelty of the invention will be evident hereinafter.

In the drawings which illustrate the presently preferred embodiment and mode of operation of the invention and in which the same or similar reference characters refer to the same or similar parts throughout the several views:

FIGURE 1 is a view of the assembly of the liner hanger and setting tool, partly in elevation and partly in longitudinal section, as it appears when suspended in a well casing prior to setting.

FIGURE 2 is a view similar to FIGURE 1 showing the liner hanger with the slips set in the casing and the setting tool positioned for setting the packing.

FIGURE 3 is a view similar to FIGURES 1 and 2 showing the liner hanger after completion of setting both the slips and the packing in the casing and with the setting tool positioned for effecting its release and withdrawal from the liner hanger.

FIGURE 4 is a cross sectional view taken on line 4—4 of FIGURE 1.

FIGURE 5 is a cross sectional view taken on line 5—5 of FIGURE 3.

FIGURE 6 is an enlarged fragmentary detailed view, partly in elevation and partly in longitudinal section of the slip actuating mechanism portion of FIGURES 1, 2, and 3.

FIGURE 7 is a view, partly in elevation and partly in longitudinal section, showing a modified form of a portion of the slip actuating mechanism of the liner hanger.

FIGURE 8 is a view similar to FIGURE 7 showing another modification of a portion of the slip actuating mechanism of the liner hanger.

The apparatus of FIGURES 1 to 6 inclusive is as follows:

Referring first mainly to FIGURE 1, the apparatus assembly there shown comprises two main components, namely, a liner hanger, shown generally at 10, and a setting tool, shown generally at 20. The setting tool 20 is retrievably suspended in the well upon an operating string 12, and the liner hanger into which the setting tool 20 extends is, in turn, detachably supported thereon in readiness for setting in a casing 14 of a typical well or earth bore hole.

The liner hanger 10 which forms an elongated, generally tubular assembly, having a substantially uniform outside diameter from end to end thereof suitable for reasonably free running into casing and with clearance suitable for setting of packing therebetween, comprises in order from bottom end to top thereof, a hanger adapter sub 16 connected by means of left hand threads 21 into the lower end of a hanger body 22, the top end of which, in turn, is threadedly coupled at 24 to the lower end of a packing sleeve 26, the upper end of which is finally connected by an elongated right hand threaded section 28 into the lower end of a screw-down packing compression head 30. The adapter sub 16 is provided within the lower end portion thereof with threads 18 for connection thereto of a cage spring assembly (not shown) and a liner or the like tubular member or other apparatus to be suspended therebelow in the well.

Immediately above the before mentioned left hand threads 21 an extending upwardly as a continuation thereof within the lower end of the hanger body 22 is a left hand threaded section, as shown at 32, of sufficient length to threadedly and longitudinally adjustably carry therewithin a concentric, slip actuating sleeve 34. The bore of the slip actuating sleeve 34 is formed with a number of diametrically opposite, longitudinally extending recesses or slots 36 for engagement by bow springs 37 for rotating the slip actuating sleeve on the threads 32 relative to the hanger body, whereby the longitudinal position of the sleeve 34 may be shifted, as more fully described hereinafter.

The upper end of the slip actuating sleeve 34 is coupled in longitudinally fixed, but rotatably slidably relation with the lower end of an interconnecting ring 38 by means of a number of set screws 40, which extend radially from a flanged portion 42 of the interconnecting ring 38 into circumferentially slidable engagement within an annular groove 44 formed around the upper edge of the slip actuating sleeve 34, as best shown in FIGURE 6. The slip actuating sleeve 34 is thus rotatable upon threads 32 for longitudinal movement without imparting rotational movement to the interconnecting ring 38.

Longitudinally slidably contained within the bore of the hanger body 22 adjacent the upper end of the slip actuating sleeve 34 is a slip rein anchor sleeve 46, which is slidably supported at its lower end within the bore of the before mentioned interconnecting ring 38, and its upper end within a reduced diameter section of the bore of the hanger body, as shown at 50. Enclosed within the hanger body 22 by the before mentioned slip rein anchor sleeve 46 and the interconnecting ring 38, is an annular cavity which, in effect, is divided into an upper portion 51 and a lower portion 53 by an annular slip rein anchor ring 54 formed integrally with the exterior, mid-section of the said slip rein anchor sleeve 46. Contained and equally circumferentially spaced apart within the lower portion 53 of the annular cavity are a plurality of longitudinally extending helical springs 56, retained in such positions by means of a corresponding number of circumferentially spaced apart lower and upper cylindrical stubs 58 and 59 formed integrally with the upper end of the interconnecting ring 38 and the lower edge of the slip rein anchor ring 54, respectively. The upper and lower ends of the helical springs 56 are formed with laterally inwardly extending terminal attachment portions which extend into anchor holes 55 and 57 formed diametrically through the upper and lower stubs 59 and 58, respectively, as best shown in FIGURE 6. The helical springs 56 are thus adapted to transmit either compression or tension forces between the interconnecting ring 38 and the slip rein anchor ring 54.

Anchored at their lower ends to the outer edge of the slip rein anchor ring 54 by means of radial screws 60 are a number of slip reins 62 which extend upwardly therefrom through upper annular cavities, as shown at 51, and thence slidably through longitudinal passages 64 into a corresponding number of circumferentially spaced apart slip recesses 68, where each such slip rein is connected at its upper end to the lower end of a wedge shaped, wickered casing slip 66. Each slip recess 68 is formed with an upwardly, outwardly sloping slip wedging bottom surface 70 upon which the inner surface of the slip is longitudinally slidably supported.

The upper end of the hanger body 22 makes threaded connection at 24, as before mentioned, to the lower end of the packing sleeve 26. The intermediate portion of the exterior surface of the packing sleeve 26 is formed with a smooth, cylindrical interval of reduced outside diameter, as shown at 72, terminating at its lower end in an inwardly beveled shoulder 74 and terminating in effect at its upward end at the lower end of the threaded section 28 and the lower annular edge of the screw-down packing compression head 30. Encircling the said portion of reduced diameter 72 of the packing sleeve 26 and

5 abutting the lower annular edge of the packing compression head 30 is a floating packing compression ring 78. A plurality of resilient packing rings 76 also encircle section 72 and normally in their unexpanded condition extend between the shoulder 74 and the lower end of the compression ring 78 flush with the maximum outside diameter of the packing sleeve 26 and the liner hanger body 10, as shown in FIGURE 1. In operation, longitudinal compressive force is applied to the packing rings 76 between the packing compression head 30 and the shoulder 74 to compress the packing rings 76 longitudinally and thereby expand them laterally into sealing engagement with the inside surface of the surrounding casing.

10 The upper end of the packing compression head 30 is beveled in a downwardly converging direction, as shown at 80, to facilitate the entrance therein of the setting tool and any tubing or other apparatus which may subsequently be run into or through the liner hanger. The upper end portion of the pack-off head 30 is also formed with a plurality of longitudinally extending, rectangular shaped, clutch slots 82 for engagement by correspondingly positioned and shaped clutch dogs 83 of a clutch nut 84 fixed to the upper end of the setting tool, as hereinafter more fully described.

15 The setting tool 20 comprises an elongated, generally tubular assembly having a maximum outside diameter permitting it to extend through the bore of the liner hanger 10, as best shown in FIGURES 1 and 2.

20 The upper end of the setting tool carries the before mentioned clutch nut 84, the upper end of which makes threaded connection at 86 with the lower end of the before mentioned operating string 12 from which the whole casing hanger and setting tool assembly is initially suspended and by means of which the liner hanger and setting tool is manipulated. Formed integrally with the clutch nut 84 and located about the intermediate outside circumference thereof are a plurality of rectangular, downwardly extending clutch dogs 83 adapted when clutch nut 84 is lowered into engagement with the top of the pack-off head 30 to engage clutch slots 82 therein, for rotation of the pack-off head 30 relative to the balance of the liner hanger body in the operation of setting the hanger.

25 Threadedly connected at 90 to the lower end of the clutch nut 84 and normally extending downward therefrom into the bore of the liner hanger body and threadedly connected together in end to end relation, is a spacer sub 92, a threaded coupling 94, and a kelly member 96. The kelly member 96 is formed at its upper and lower 30 end portions 98 and 100, respectively, with round or cylindrical exterior sections, and along an intermediate portion thereof with a hexagonal exterior section 102. Threadedly connected at 109 to the lower end of the kelly member 96 is a cylindrical setting tool spring mandrel 106, the lower extended portion 108 of which is of reduced diameter relative to the upper portion thereof, thereby forming at the juncture of the upper and lower positions thereof a downwardly facing annular shoulder 110. Formed in said shoulder 110 is a downwardly facing annular undercut groove 112 adapted to longitudinally, slidably receive the upper ends 114 of each of a plurality of bow springs 116.

35 Longitudinally slidably positioned on the lower portion 108 of the setting tool spring mandrel 106 is a spring cage ring 118. The spring cage ring 118 is provided in the inner bore thereof with a plurality of circumferentially spaced apart slots extending longitudinally therethrough, each such slot receiving the lower end 120 of each of the bow springs 116. A plurality of set screws, as shown at 122, extend radially through the spring cage ring 118 and centrally through holes in each of the lower ends of the bow springs and into locking contact with the exterior surface of the lower portion 108 of the spring mandrel 106, thereby fixing the lower 40 ends of the bow springs in the spring cage ring and

also fixing the spring cage ring longitudinally immovable upon said lower portion of the setting tool spring mandrel. It will be noted that bow springs 116 are formed with intermediate, laterally extended straight sections 116a which, in the relative positions of the liner hanger and setting tool shown in FIGURE 1, make locking engagement within the before mentioned slots 36 in the bore of the slip actuating sleeve 34.

The lower end of the lower portion 108 of the setting tool spring mandrel 106 is threaded at 124 for connection to any device or additional equipment to be suspended from the lower end of the setting tool.

Surrounding the kelly member 96 and making threaded connection by means of left hand, square threads 126 in the upper end of the hanger body portion 22 is a running and releasing nut 128. The running and releasing nut 128 is formed with a hexagonal passage 129 therethrough with which the intermediate, hexagonal section 102 of the kelly member 96 makes non-rotatable, longitudinally slidable engagement, when positioned in an intermediate position as shown in FIGURE 3. When the setting tool is positioned within the liner hanger, as shown in either FIGURE 2 or FIGURE 1, however, the cylindrical end sections 98 or 100, respectively, are located within the hexagonal passage 129 through the running and releasing nut 128 and thus in operation in such positions, as hereinafter described, the setting tool may be rotated within the liner hanger without rotating the running and releasing nut 128.

Retained in an undercut recess 130 formed in the lower end of the running and releasing nut 128 is a thrust swivel bearing 132. When the liner hanger and setting tool are in a suspended position prior to setting, as shown in FIGURE 1, the weight of the liner hanger assembly is carried through the square threads 126, the running and releasing nut 128, and through the swivel bearing 132 to an annular shoulder 134 formed on the upper end of the setting tool spring mandrel 106 and thence through screwed joint 109, kelly member 96, coupling 94, spacer sub 92, threaded joints 90 and 86 to the operating string 12.

Operation of the apparatus of FIGURES 1 to 6 inclusive:

The liner hanger 10 containing the setting tool 20 is first lowered into the well casing on the operating string 12 to the location therein where it is to be set, at which point the setting tool 20 and liner hanger assembly 10 will be suspended upon the operating string 12 with the casing hanger and setting tool occupying the relative positions shown in FIGURE 1, in readiness for setting. At this initial stage in the setting operation, the weight of the liner hanger assembly 10 is supported on the shoulder 134 of the setting tool mandrel 106 through the running and releasing nut 128 and swivel bearing 132, and the straight sections 116 of bow springs 37 are positioned in engagement with the slots 36 in the bore of the slip actuating sleeve 34.

Next, right hand rotation is imparted through the operating string 12 to the setting tool assembly 20 and thence through the bow spring 37 to the slip actuating sleeve 34, with the result that the slip actuating sleeve 34 is screwed upwardly on the left hand threads 32 within the lower end of the hanger body 22. Meanwhile, rotation of the hanger body is prevented by means of a cage spring or the like device (not shown) making frictional engagement with the inside of the surrounding casing or bore hole wall. Such cage spring may be suspended below the hanger body by attachment of threads 18 to the hanger adapter sub 16.

The resultant upward movement of the slip actuating sleeve 34 is transmitted through the interconnecting ring 38, helical springs 56, slip rein anchor ring 54, and slip reins 62 to slips 66, which slips are thereby caused to slide upwardly and outwardly upon the slip wedging sur-

face 70 into engagement with the inside surface of the casing 14, as shown in FIGURE 2, at which time the hanger assembly is supportable within the casing upon the slips. A slight lowering of the setting tool 20 by lowering the operating string 12 causes the slips 66 to be wedged into gripping engagement with the surrounding casing, whereupon the weight of the liner hanger, liner and the like apparatus attached to the liner hanger, is transferred to the casing, and the liner hanger is no longer dependent for support upon the setting tool and operating string.

Following the before described setting of the slips 66, the operating string 12 is lowered until the clutch nut 84, at the top of the setting tool, comes to rest upon the top of the packing compression head 30 at the top of the liner hanger assembly and clutch dogs 83 are thereby placed in engagement with the clutch slots 82, at which time the liner hanger and setting tool occupy the relative positions shown in FIGURE 2. It is to be noted that in the latter relative positions of the hanger and setting tool the upper round section 98 of the kelly member 96 is located within the hexagonal passage 129 through the running and releasing nut 128 and thus is rotationally out of engagement therewith.

Next, the setting tool assembly is again imparted right hand rotation by the operating string 12 thereby, through the action of the clutch nut 84, screwing down the packing compression head 30 upon the threads 28 and thereby forcing the floating packing compression ring 78 downward toward the shoulder 74. Longitudinal compression force is thus applied to the packing rings 76 to expand them laterally into sealing engagement between the packing sleeve section 26 and the inside surface of the surrounding casing 14.

Next, upon completion of the packing setting operation, the setting tool assembly is elevated by the operating string to a position relative to the liner hanger, where the intermediate hexagonal section 102 of the kelly member 96 extends through and in engagement with the matching hexagonal passage 129 in the running and releasing nut 128, as shown in FIGURES 3 and 5.

Next, the setting tool assembly, including the kelly member 96 is again imparted right hand rotation through the operating string 12, whereupon the running and releasing nut 128 is rotated relative to the hanger body 22 upon the left hand threads 126, and thereby is released from connection with the liner hanger body, after which the setting tool is free to be withdrawn from the liner hanger and from the well, leaving the liner hanger firmly set and packed off in the well casing.

If it is desired to release the liner hanger for movement to another position in the well casing, the setting tool assembly 20, if it has been previously withdrawn, is lowered into the liner hanger to a position approximating that shown in FIGURE 3, at which position the lower end of the running and releasing nut 128 initially rests upon the upper end of the square, left hand threads 126, following which, by careful left hand rotation of the operating string and setting tool, the nut 128 is threaded into the threads 126 and thereby into connection with the upper end of the liner hanger body to the same position shown in FIGURE 3. Following the thus re-established connection between the running and releasing nut 128 and the liner hanger, the setting tool is elevated to a position relative to the liner hanger and running and releasing nut 128 approximating that shown in FIGURE 1, whereupon the condition for supporting the liner hanger upon the setting tool through the thrust bearing 134 is re-established and the bow springs 37 are also repositioned in engagement with the slots 36 within the bore of the slip actuating sleeve 34. Following this, left hand rotation is again imparted to the setting tool through the operating string 12 with resultant left hand rotation of the slip actuating sleeve 34 relative to the liner hanger body which screws the slip actuating sleeve 34 down-

ward therin. This downward screwing of the actuating sleeve pulls the interconnecting ring 38 downward and introduces tension in the helical springs 56 which tension is, in turn, transferred to the slip rein anchor ring 54 and thence to the slip reins 62 and to the slips 66.

The setting tool is then elevated slightly to apply lifting force to the liner hanger through the kelly, kelly swivel bearing 132, and running and releasing nut 123 sufficient to release the loading upon the slips 66, whereupon the slips are freed from wedging engagement with the casing sufficiently to be pulled downward by the before described tension in springs 56 and retracted within their slip recesses 68, thereby to re-establish the relative positions of the apparatus shown in FIGURE 1. The whole setting tool and liner hanger assembly can then be either withdrawn from the well or moved to a new location within the well casing and the before described setting operations repeated.

The apparatus of FIGURES 7 and 8 are as follows:

Referring now primarily to FIGURE 7, a modified form of the liner hanger assembly similar in some respect to that hereinbefore described in connection with FIGURES 1 to 6 inclusive, is shown. In the liner hanger assembly of FIGURE 7, the construction is such as to form an elongated, generally tubular assembly having a substantially uniform inside and outside diameter and comprising from bottom end to top thereof a hanger adapter sub 16 which is threaded by left hand threads at 21a into the lower end of a hanger body 22a and the top end of which is connected by threads 135 to an upper hanger body portion 136 which, in turn, is adapted to be threaded coupled at 24a to the lower end of the packing sleeve which may be of the same construction as the packing sleeve 26 hereinbefore described in connection with FIGURES 1 to 6 inclusive.

Immediately above the before mentioned threads 21a and extending upwardly therefrom within the lower end of the hanger body 22a is a continuation of the left hand threaded section 32a of sufficient length above the connection with the liner adapter sub 16 to carry threadedly and longitudinally adjustably therein a concentric, left hand threaded slip actuating sleeve 34a. The bore of the slip actuating sleeve 34a is formed with a number of diametrically opposite, longitudinally extending recesses or slots 36a similar to slots 36 hereinbefore described in connection with the slip actuating sleeve 34, for engagement by bow springs of the setting tool for rotating the slip actuating sleeve 34a on the threads 32a relative to the lower hanger body portion, whereby the longitudinal position of the sleeve 34a may be shifted longitudinally therein in the same manner as hereinbefore described in connection with the slip actuating sleeve 34. The slip actuating sleeve 34a is similar to the hereinbefore described slip actuating sleeve 34, except as hereinafter described.

The upper end portion 138 of the slip actuating sleeve 34a is of reduced outside diameter relative to the lower portion thereof, forming at the change in diameter junction thereof an upwardly facing annular shoulder 137. The upper end portion 138 of the slip actuating sleeve 34a makes a longitudinally sliding fit within an intermediate bore section 140 of the hanger body 22a which is of reduced inside diameter relative to the inside diameter 142 of the adjacent bore of the lower portion of the hanger body, forming at the change in diameter junction thereof a downwardly facing annular shoulder 144 opposite the beforementioned upwardly facing annular shoulder 137. A lower annular chamber 146 of variable volume is thus formed between the upper and lower annular shoulders 137 and 144 and between the surface of the inside diameter 142 of the hanger body and the surface of the outside diameter of the slip actuating sleeve 138, respectively. O-ring seals are provided for the annular chamber 146, as shown at 148 and 150.

The upper end portion of the hanger body, at a section 152 extending downwardly from threaded portion 135 and downwardly from the lower end 153 of the upper portion 136 of the hanger body, is of reduced outside diameter relative to the balance of the lower portion of the hanger body, forming at the change in diameter junction thereof an upwardly facing annular shoulder 154. Longitudinally slidably upon the section 152 of the liner hanger body between shoulder 154 and downwardly facing lower end 153 is an annular slip rein ring 156.

The slip rein ring 156 has formed integrally therewith and extending axially upwardly and downwardly therefrom sleeve members 158 and 160, respectively, of larger inside diameter than that of the slip rein anchor ring portion thereof, sleeve member 158 being longitudinally slidable over the lower end portion of the upper portion 136 of the hanger body and the sleeve 160 being longitudinally slidable over an intermediate, exterior section 162 of the lower portion of the hanger body 22a. An annular chamber 164 of variable volume is thus formed between shoulder 154 of the hanger body and the lower annular end 166 of the slip rein ring 156. O-ring seals are provided for the annular chamber 164, as shown at 168 and 170.

A plurality of drilled ducts extend longitudinally between the annular chambers 146 and 164, one of which is shown in dotted lines 172, whereby fluid, preferably oil, under pressure may be transferred between the chambers 146 and 164, as hereinafter described.

A plurality of slip reins 174 extend upwardly from the upper slip rein ring sleeve 158 through longitudinal guide slots 176 formed in the exterior surface of the upper hanger body, adjacently exterior of the threaded connection 135 and into circumferentially spaced apart slip recesses 68a, where each slip rein is connected at its upper end to the lower end of a wedge shaped, serrated casing slip 66a, as hereinbefore described in connection with the structure shown in FIGURES 1 to 6 inclusive.

Referring now primarily to FIGURE 8, another modified form of the liner hanger assembly is shown which is similar to that of FIGURE 7, the principal difference being that instead of the slip rein ring being located exterior of the hanger body, as shown at 156 in FIGURE 7, it is located internally, as shown at 156b in FIGURE 8 and in a manner similar to that shown in FIGURE 1. In this latter construction, the upper end portion 138b of the slip actuating sleeve 34b is of reduced outside diameter relative to the lower portion thereof, forming at the change in diameter junction thereof an upwardly facing annular shoulder 137b. The upper end portion 138b of the slip actuating sleeve 34b makes a longitudinally sliding fit within the lower portion of the bore 140b of a spacer sleeve 182 which is fastened inside the hanger body by a plurality of set screws, as shown at 184 and 186. The lower end of the spacer sleeve 182 forms a downwardly facing, annular shoulder 144b opposite the upwardly facing annular shoulder 137b. A lower annular chamber 146b of variable volume is thus formed between the upper and lower annular shoulders 137b and 144b and enclosed by the surfaces of the inside diameter 142b of the hanger body and the outside diameter of the slip actuating sleeve 138b, respectively. O-ring seals are provided for the annular chamber 146b, as shown at 190 and 192.

The bore of the upper end portion of the hanger body, at a section shown at 152b, is of reduced inside diameter relative to the balance of the bore of the lower portion of the hanger body. Longitudinally slidably within the bore section 152b is an annular slip rein ring 156b. The slip rein ring 156b has formed integrally therewith, and extending axially upwardly and downwardly therefrom, slip rein anchor ring sleeve members 158b and 160b, respectively, sleeve member 158b being longitudinally slidable within a bore portion 153b of the hanger body, and the sleeve 160b being longitudinally slidable within the upper

portion of the bore 140b of the spacer sleeve 182. An annular chamber 164b of variable volume is thus formed between the upper end 154b of the spacer sleeve 182 and the lower annular end 166b of the slip rein ring 156b and enclosed between the bore of the sleeve 160b and the interior surface of the hanger body. O-ring seals are provided for the annular chamber 156b, as shown at 168b and 170b.

A plurality of drilled ducts extend longitudinally between the annular chambers 146b and 164b, one of which is shown in dotted lines 172b, whereby fluid, preferably oil, under pressure may be transferred between the chambers, as hereinafter described.

A plurality of slip rein 174b extend upwardly from the slip rein ring 156b through longitudinal guide slots 176b formed through the exterior surface of the hanger body and into circumferentially spaced apart slip recesses 68b, where each slip rein is connected at its upper end to the lower end of a wedge shaped, wickered casing slip 66b, as hereinbefore described in connection with the structure shown in FIGURES 1 to 7 inclusive.

Operation of the apparatus of FIGURE 7 is as follows:

The setting tool is initially positioned in the liner hanger body 22a, shown in FIGURE 7, corresponding to the position thereof, shown in FIGURE 1, and right hand rotation is then imparted through the operating string 12 to the setting tool assembly 20 and thence through the bow springs 37 in engagement with the slots 36a to the slip actuating sleeve 34a with the result that the slip actuating sleeve 34a is screwed upwardly on the left hand threads 32a. Meanwhile, rotation of the hanger body is prevented, as described in connection with the operation of the apparatus of FIGURES 1 to 6, inclusive, by means of a cage spring or the like device (not shown) attached to threads 18 of the hanger adapter sub 16 and which makes frictional engagement with the inside of the casing or bore hole wall.

The rotation of the slip actuating sleeve 34a causes shoulder 137 to move upwardly relative to the shoulder 144, thereby reducing the volume of chamber 146 and forcing fluid, preferably oil, therefrom under pressure through the ducts 172 into the chamber 164, thereby causing the chamber 164 to be extended in length and thereby causing the slip rein ring 156 to be moved upwardly. The resultant upward movement of the slip rein actuating ring 156 is transmitted through sleeve 158 to the slip reins 174a and thence to the slips 66a which are thereby caused to slide upwardly and outwardly upon the slip wedging surfaces 70a into gripping engagement with the inside surface of the casing, as shown in FIGURE 2. The hanger assembly is then supportable within the casing upon the slips 66a and no longer is dependent for support upon the setting tool 20 and operating string 12. The balance of the setting and releasing operations of the liner hanger and the packing is performed in the same manner as hereinbefore described in connection with FIGURES 1 to 6 inclusive.

Operation of the apparatus of FIGURE 8 is as follows:

The setting tool is initially positioned in the liner hanger body shown in FIGURE 8 corresponding to the position thereof shown in FIGURE 1, and right hand rotation is then imparted through the operating string 12 to the setting tool assembly 20 and thence through the bow springs 37 to the slip actuating sleeve 34b with the result that the slip actuating sleeve 34b is screwed upwardly, relative to the hanger body 22b, on the left hand threads 32b. Meanwhile, during rotation of the slip actuating sleeve, rotation of the hanger body 22b is prevented, as described in connection with the operation of apparatus of FIGURES 1 to 6 inclusive, by means of a cage spring or the like device (not shown) connected to threads 18 of the hanger adapter sub 16 and which makes frictional engagement with the inside surface of the surrounding casing or bore hole wall.

Rotation of the slip actuating sleeve 34b with the resultant upward movement thereof on threads 32b causes

shoulder 137b to move upwardly relative to the shoulder 144b of the spacer sleeve, thereby reducing the volume of chamber 146b and forcing fluid, preferably oil, therefrom under pressure through the ducts 172b into the chamber 164b, thereby causing the chamber 164b to be extended in length and thereby causing the slip rein actuating ring 156b to move upwardly. The resultant upward movement of the slip rein actuating ring 156b is transmitted through the slip reins 174b to the slips 66b, which are thereby caused to slide upwardly and outwardly upon the slip wedging surfaces 70b into gripping engagement with the inside surface of the casing to positions corresponding to that shown in FIGURE 2. At this stage of the hanger setting operation, the assembly is supportable within the casing upon the slips and thus is no longer dependent for support upon the setting tool and operating string 12. The subsequent operations of setting the liner hanger and packing and releasing of the setting tool may be performed in the same manner and in the same sequence as herebefore described in connection with the apparatus of FIGURES 1 to 6 inclusive.

The liner hanger of this invention including the pack-off features thereof, is not only advantageous in connection with the setting in a well of more or less conventional perforated pipe, but is also adapted to greatly improve and facilitate a number of other well completion operations such as, for example, cementing and ground packing. The versatile characteristics of this liner hanger, pack-off means, and setting tool assembly permit a variety of different operations within the well without costly and untimely pulling and screwing of different down hole tool set-ups.

It is to be understood that the foregoing is illustrative only, and that the invention is not limited thereby, but includes all modifications thereof in the scope of definition of the appended claims.

I claim:

1. A liner hanger and setting tool assembly comprising: a hanger body; an annular sleeve member threaded-40ly coupled concentrically within said body and thereby movable longitudinally therein by rotation relative to said body; slip means and slip expander means carried by said body, said slip means being movable on said expander means between retracted and extended positions relative thereto; means coupling said annular sleeve member to said slip means, whereby longitudinal movement of said sleeve member attendant upon rotation of said sleeve member relative to said body moves said slip means on said expander means between said retracted and extended positions; and setting tool means connected to said body and rotatable relative thereto, said setting tool means including means detachably engaging said annular sleeve member for transmitting rotation of said setting tool to said sleeve member relative to said body, thereby to move said slips as aforesaid.

2. A liner hanger and setting tool assembly comprising: a hanger body; an annular sleeve member threaded-60ly, detachably coupled concentrically within said body; setting tool means initially extending into said body and through said sleeve member, said tool means and sleeve member including means permitting longitudinally slid-65able movement between limits relative to one another and rotatable relative to one another when at a first predetermined longitudinal position relative to one another between said limits, whereby said setting tool means is longitudinally, slidably connected to said body and rotatable relative thereto when at said first predetermined longitudinal position; means coupling said setting tool means and said sleeve member together non-rotatable relative to one another when said sleeve member and tool means are moved to a second predetermined longitudinal position relative to one another, whereby said setting tool means may be rotated relative to said sleeve member and said body when in said first longitudinal position relative to one another and whereby said sleeve

member may be rotated by said tool means relative to said body to detach said sleeve member from said body and thereby disconnect said tool means from said body when said tool means and body are in said second predetermined position relative to one another.

3. A liner hanger and setting tool assembly comprising: a hanger body; an annular sleeve member threadedly, detachably coupled concentrically within said body; setting tool means initially extending into said body and through said sleeve member, said tool means and sleeve member including means permitting longitudinally slideable movement between limits relative to one another and rotatable relative to one another, when at either of said limits, whereby said tool means is longitudinally, slidably connected to said body and rotatable relative thereto at either of said limits; means coupling said tool means and said sleeve member together non-rotatable relative to one another, when said sleeve member and tool means are moved to a predetermined longitudinal position relative to one another immediate said limits, whereby said tool means may be rotated relative to said sleeve member and said body when said tool means and sleeve member are positioned at either of said limits relative to one another and whereby said sleeve member may be rotated by said tool means relative to said body to detach said sleeve member from said body and thereby disconnect said tool means from said body when said tool means and body are in said predetermined longitudinal position relative to one another intermediate said limits.

4. A liner hanger and setting tool assembly comprising: a hanger body; a first annular variable fluid containing chamber in said body; an annular sleeve member threadedly coupled concentrically within said body and thereby movable longitudinally by rotation thereof relative to said body; means coupling said sleeve member with said first chamber, whereby longitudinal movement thereof resulting from said rotation changes the volume of said chamber; a second annular variable volume fluid containing chamber within said body; duct means interconnecting said first chamber and said second chamber; slip means carried by said body and movable between retracted and extended positions relative thereto; and means coupling said second chamber to said slip means, whereby change in volume of said second chamber attendant upon change of volume of said first chamber moves said slip means between said retracted and extended positions.

5. A liner hanger and setting tool assembly comprising: a hanger body; a first annular variable volume chamber in said body; an annular sleeve member threadedly coupled concentrically within said body and thereby movable longitudinally by rotation thereof relative to said body; means coupling said sleeve member with said first chamber, whereby longitudinal movement thereof resulting from said rotation changes the volume of said chamber; a second annular variable volume chamber within said body; duct means interconnecting said first chamber and said second chamber; slip means carried by said body and movable between retracted and extended positions relative thereto; and means coupling said second chamber to said slip means, whereby change in volume of said second chamber attendant upon change of volume of said first chamber moves said slip means between said retracted and extended positions.

6. A liner hanger and setting tool assembly comprising: a hanger body; a first annular sleeve member threadedly, detachably coupled concentrically within said body; setting tool means initially extending into said body and through said first sleeve member, said tool means and first sleeve member being longitudinally slideable between limits relative to one another and rotatable relative to one another when at either of said limits, whereby said setting tool is longitudinally, slidably connected to said body; a second annular sleeve member threadedly coupled concentrically within said body; casing gripping

means carried by said body and movable between retracted and extended positions relative thereto; means interconnecting said second sleeve member and said casing gripping means, whereby longitudinal movement of said second sleeve member attendant upon rotation thereof relative to said body moves said casing gripping means between retracted and extended positions; means coupling said tool means and said second sleeve member together non-rotatable relative to one another when said tool means and said first sleeve member are moved to one of said limits relative to one another, whereby rotation of said tool means relative to said body rotates said second sleeve member relative to said body, and said casing gripping means is thereby moved between said retracted and extended positions; means coupling said tool means and said first sleeve member together non-rotatable relative to one another when said tool means and said first sleeve member are moved to a predetermined longitudinal position relative to one another intermediate said limits, whereby rotation of said tool means relative to said body rotates said first sleeve member relative to said body to detach said first sleeve member from said body and thereby disconnect said tool means from said body.

7. A liner hanger and setting tool assembly comprising: a hanger body; a first annular sleeve member threadedly, detachably coupled concentrically within said body; setting tool means initially extending into said body and through said first sleeve member, said tool means being slideable longitudinally through said first sleeve member between limits and rotatable relative to said first sleeve member when positioned adjacent either of said limits; a second annular sleeve member threadedly coupled concentrically within said body and thereby movable longitudinally therein by rotation relative to said body; casing gripping means carried by said body and movable between retracted and extended positions relative thereto; means interconnecting said second sleeve member and said gripping means, whereby such longitudinal movement of said second sleeve member attendant upon its rotation relative to said hanger body moves said gripping means between retracted and extended positions; means actuatable, by positioning said setting tool adjacent one of said limits relative to said first sleeve member, to couple said tool means and said second sleeve member together non-rotatable relative to one another, whereby rotation of said tool means relative to said body rotates said second sleeve member relative to said body, and said gripping means is thereby in turn moved between said retracted and extended positions; packing means carried by said body and deformable between retracted and extended positions; rotatable compression means to deform said packing means between such retracted and extended positions; means, actuatable by positioning said setting tool adjacent the other of said limits relative to said first sleeve member, to couple said tool means to said compression means, whereby rotation of said tool means relative to said body rotates said compression means relative to said body, and said packing means is thereby in turn deformed between said retracted and extended positions; means, actuatable by positioning said setting tool at a longitudinal position relative to said first sleeve member intermediate said limits, to couple said tool means and said first sleeve means together non-rotatable relative to one another, whereby rotation of said tool means relative to said body rotates said first sleeve member relative to said body, to disconnect said first sleeve member from said body and thereby detach said tool means from said body.

8. A liner hanger and setting tool assembly comprising: a hanger body; a first annular sleeve member threadedly, detachably coupled concentrically with said body; setting tool means initially extending through said first sleeve member, said tool means being slideable longitudinally through said first sleeve member between upper and lower limits and rotatable relative to said first sleeve

member when positioned adjacent either of said limits; a second annular sleeve member threadedly coupled concentrically with said body and thereby movable longitudinally relative to said body by rotation relative to said body; casing gripping means carried by said body and movable between retracted and extended positions relative thereto; means interconnecting said second sleeve member and said gripping means, whereby such longitudinal movement of said second sleeve member attendant upon its rotation relative to said hanger body moves said gripping means between retracted and extended positions; means actuatable, by positioning said setting tool adjacent the upper one of said limits relative to said first sleeve member, to couple said tool means and said second sleeve member together non-rotatable relative to one another, whereby rotation of said tool means relative to said body rotates said second sleeve member relative to said body, and said gripping means is thereby in turn moved between said retracted and extended positions; packing means carried by said body and deformable between retracted and extended positions; rotatable compression means to deform said packing means between said retracted and extended positions; means, actuatable by positioning said setting tool adjacent the lower one of said limits relative to said first sleeve member, to couple said tool means to said compression means, whereby rotation of said tool means relative to said body rotates said compression means relative to said body and said packing means is thereby in turn deformed between said retracted and extended positions; means, actuatable by positioning said setting tool at a longitudinal position relative to said first sleeve member intermediate said upper and lower limits, to couple said tool means and said first sleeve member together non-rotatable relative to one another, whereby rotation of said tool means relative to said body rotates said first sleeve member relative to said body, to disconnect said first sleeve member from said body and thereby detach said tool means from said body.

9. A liner hanger and setting tool assembly comprising: 40 a hanger body;

gripping means carried by said hanger body and extendable therefrom into engagement with a surrounding casing;

packing means carried by said hanger body and expandable therefrom into engagement with a surrounding casing;

a setting tool initially extending axially into said hanger body with freedom for limited axial sliding movement relative to said hanger body;

means for initially supporting said hanger body upon said setting tool in a first longitudinal position relative to one another and with freedom of rotation of said hanger body and said setting tool relative to one another;

means interengaging said setting tool and said hanger body while said setting tool and said hanger body are in said first longitudinal position relative to one another and actuatable by rotation of said setting tool in a predetermined direction relative to said hanger body for extending said gripping means into engagement with a surrounding casing;

means interengageable with said setting tool and said hanger body by positioning said setting tool and hanger body in a second longitudinal position relative to one another and actuatable by rotating said setting tool in the said same predetermined direction relative to said hanger body, for expanding said packing means into engagement with a surrounding casing;

and means interengageable with said setting tool and said hanger body by positioning said setting tool and said hanger body in a third longitudinal position relative to one another and actuatable by rotating said setting tool in the same predetermined direction rela-

tive to said hanger body, for releasing and permitting withdrawal of said setting tool from said hanger body.

10. A liner hanger and setting tool assembly comprising:

a hanger body; gripping means carried by said hanger body and extendable therefrom into gripping engagement with a surrounding casing;

a setting tool initially extending axially into said hanger body with freedom for limited axial sliding movement relative thereto;

means for initially supporting said hanger body upon said setting tool in a first longitudinal position relative to one another and with freedom of rotation of said hanger body and said setting tool relative to one another;

means interengaging said setting tool and said hanger body while said setting tool and said hanger body are in said first position relative to one another and actuatable by rotation of said setting tool in a predetermined direction relative to said hanger body for extending said gripping means into engagement with a surrounding casing;

means interengageable with said setting tool and hanger body by positioning said setting tool and hanger body in a second longitudinal position relative to one another and actuatable by rotating said setting tool in said predetermined direction relative to said hanger body while in said second longitudinal position, for releasing and permitting withdrawal of said setting tool from said hanger body.

11. A liner hanger and setting tool assembly comprising:

a hanger body; gripping means carried by said hanger body and extendable into gripping engagement with a surrounding casing;

a setting tool initially extending axially into said hanger body with freedom for limited axial sliding movement relative thereto;

means for initially supporting said hanger body upon said setting tool in a first longitudinal position relative to one another and with freedom of rotation of said hanger body and setting tool relative to one another;

means interengaging said setting tool and said hanger body when said setting tool and said hanger body are in said first position relative to one another and actuatable by rotation of said setting tool in a predetermined direction relative to said hanger body for extending said gripping means into supporting engagement with a surrounding casing, whereby said setting tool can be lowered relative to said hanger body while said hanger body is supported by said casing, thereby positioning said setting tool and hanger body in a second longitudinal position relative to one another;

means interengageable with said setting tool and said hanger body by positioning said setting tool and said hanger body in said second longitudinal position relative to each other, while said hanger body is supported by said casing and actuatable by rotation of said setting tool in said same predetermined direction relative to said hanger body for releasing and permitting withdrawal of said setting tool from said hanger body.

12. A linear hanger and setting tool assembly comprising:

a hanger body; gripping means carried by said hanger body and extendable into gripping engagement with a surrounding casing;

packing means carried by said hanger body and extendable therefrom into sealing engagement with a surrounding casing;

75

a setting tool initially extending axially into said hanger body with freedom for limited axial sliding movement relative thereto; means for initially supporting said hanger body upon said setting tool with said setting tool in a first longitudinal position relative to said hanger body and with freedom of rotation of said hanger body and setting tool relative to one another; means interengaging said setting tool and said hanger body while said setting tool and hanger body are in said first position relative to one another and actuatable by rotation of said setting tool in a predetermined direction relative to said hanger body for extending said gripping means into supporting engagement with a surrounding casing whereby said setting tool can be lowered to a second position relative to said hanger body while said hanger body is thus supported in such casing; and means interengaging said setting tool and said hanger body while said setting tool and said hanger body are in said second longitudinal position relative to one another and actuatable by rotation of said setting tool in said same predetermined direction relative to said hanger body for expanding said packing means into sealing engagement with the surrounding casing.

13. A liner hanger and setting tool assembly comprising:

a hanger body; gripping means carried by said hanger body and extendable therefrom into gripping engagement with a surrounding casing; packing means carried by said hanger body and extendable therefrom into sealing engagement with a surrounding casing; a setting tool initially extending axially into said hanger body with freedom for limited axial sliding movement relative thereto; means for initially supporting said hanger body upon said setting tool in a first longitudinal position relative to one another and with freedom of rotation of said hanger body and setting tool relative to each other; means interengaging said setting tool and said hanger body while said setting tool and hanger body are in said first longitudinal position relative to one another and actuatable by rotation of said setting tool and in a predetermined direction relative to said hanger body for extending said gripping means into supporting engagement with a surrounding casing whereby said setting tool can be lowered to a second and a third position relative to said hanger body while said hanger body is thus supported in the casing; means interengageable with said setting tool and said hanger body while said setting tool and said hanger body are in said second longitudinal position relative to one another and actuatable by rotation of said setting tool in a right-hand direction relative to said hanger body for expanding said packing means into sealing engagement with the surrounding casing; and means interengageable with said setting tool and said hanger body while said setting tool and hanger body are in a third longitudinal position relative to one another and while said hanger body is supported in the casing actuatable by rotation of said setting tool in a right-hand direction relative to said hanger body for releasing and permitting withdrawal of said setting tool from said hanger body.

14. A liner hanger and setting tool assembly comprising:

a hanger body; gripping means carried by said hanger body and ex-

tendable therefrom into gripping engagement with a surrounding casing; packing means carried by said hanger body and extendable therefrom into sealing engagement with a surrounding casing; a setting tool initially extending axially into said hanger body with freedom for limited axial sliding movement relative thereto; means for initially supporting said hanger body upon said setting tool in a first longitudinal position relative to one another and with freedom of rotation of said hanger body and setting tool relative to one another; means interengaging said setting tool and hanger body while said hanger body and setting tool are in said first longitudinal position relative to one another and actuatable by rotation of said setting tool in a right-hand direction relative to said hanger body for extending said gripping means into supporting engagement with a surrounding casing whereby said setting tool can be lowered to a second and a third position relative to said hanger body while said hanger body is thus supported in the casing; means interengageable with said setting tool and said hanger body while said setting tool and said hanger body are in said second longitudinal position relative to one another and while said hanger body is supported in said casing and actuatable by rotation of said setting tool in a right-hand direction relative to said hanger body for expanding said packing means into sealing engagement with the surrounding casing; and means interengageable with said setting tool and said hanger body while said setting tool and hanger body are in a third longitudinal position relative to one another and while said hanger body is supported in the casing actuatable by rotation of said setting tool in a right-hand direction relative to said hanger body for releasing and permitting withdrawal of said setting tool from said hanger body.

15. A liner hanger and setting tool assembly comprising:

a hanger body; an annular sleeve member threadedly coupled concentrically within said hanger body and thereby movable longitudinally therein by rotation thereof relative to said body; slip means carried by said hanger body and movable between retracted and extended positions relative thereto; means coupling said annular sleeve member to said slip means, whereby such longitudinal movement of said sleeve member attendant upon such rotation thereof relative to said hanger body moves said first slip means between said positions; and setting tool means including means interconnecting said setting tool means and said hanger body such that said setting tool means is rotatable relative to said hanger body and movable longitudinally relative thereto between limits, said setting tool means including means engaging said annular sleeve member for transmitting rotation of said setting tool to said sleeve member relative to said hanger body when said setting tool means is in a first longitudinal position between said limits, and rotationally free of engagement with said annular sleeve member when said setting tool means is in a second longitudinal position between said limits.

16. A liner hanger and setting tool assembly comprising:

a hanger body; an annular sleeve member threadedly coupled concentrically within said body and thereby movable longitudinally therein by rotation relative to said body;

slip means carried by said body and movable between retracted and extended positions relative to said body; means coupling said annular sleeve member to said slip means, whereby longitudinal movement of said sleeve member attendant upon its rotation relative to said body moves said first mentioned means between said positions; 5

setting tool means connected to said body such as to be rotatable relative thereto and movable longitudinally relative thereto between limits, said setting 10 tool means including means engaging said annular sleeve member for transmitting rotation of said setting tool to said sleeve member relative to said body when in a first longitudinal position between said limits, and rotationally free of engagement with 15

said annular sleeve member when in a second longitudinal position between said limits; and means actuatable by rotation of said setting tool means relative to said body while said setting tool means is in said second position for detaching said setting tool means from said body.
